S. AGRANAT
COMBINED CLOCK AND TIME STAMP.
APPLICATION FILED APR. 10, 1919.

1,338,413.

Patented Apr. 27, 1920.

UNITED STATES PATENT OFFICE.

SIMON AGRANAT, OF BOSTON, MASSACHUSETTS, ASSIGNOR TO JOSEPH LEVY, OF BOSTON, MASSACHUSETTS.

COMBINED CLOCK AND TIME-STAMP.

1,338,413.

Specification of Letters Patent. Patented Apr. 27, 1920.

Application filed April 10, 1919. Serial No. 289,058.

To all whom it may concern:

Be it known that I, SIMON AGRANAT, a citizen of the United States, and a resident of Boston, Massachusetts, whose post-office address is 175 Washington street, Boston, Massachusetts, have invented an Improvement in Combined Clocks and Time-
5 Stamps, of which the following description, in connection with the accompanying drawings, is a specification, like letters on the drawings representing like parts.

10 My present invention is an improvement on my prior automatic time stamp apparatus, Serial No. 274,292, filed January 31, 1919, and the object of the invention is to improve and perfect and simplify clock and time stamps of this type.

15 In my said prior application, I have explained the desirability of utilizing a separate timing element and a time stamping element which we arrange in proximity to each other and with a flexible uniting element joining the central arbor of the clock with movable means in the stamping element to reproduce the time of the clock in 20 the stamp.

25 In my present application, I have greatly simplified and improved this combination, using a separate timing element or clock but positioned in immediate proximity with the stamping device so as to give the appearance, compactness, convenience, and effect of a clock and time stamp built together; but with all the advantages of a 30 separate timing element and separate stamping element. Among these advantages are, briefly, that an inexpensive clock which may be connected with the stamping apparatus, remote from the factory,—saving shipping 35 of both timing and stamping devices, enabling different types of clocks to be utilized, eliminating the jars, wear, and tear on the clock incident to the stamping operation, and greatly simplifying as well as 40 economizing the cost of construction and marketing of time stamping apparatus.

45 A difficulty in endeavoring to unite the clock and stamping apparatus so as to appear substantially as a single unitary device 50 has been in the fact that nearly all feasible clocks must be wound from the back and it was therefore impossible to position a clock closely adjacent to the time stamp. An important feature of the present invention consists in my novel arrangement overcoming 55

this difficulty and enabling an inexpensive usual type of kitchen clock to be employed advantageously and to provide means uniting it closely with the stamping apparatus and also permitting and facilitating the 60 winding of the clock.

Referring to the drawings illustrating a preferred embodiment of the invention—

Figure 1 is a plan view of the clock and time stamping device arranged in operative 65 position; and

Fig. 2 is a side view.

Referring to my improved time stamping apparatus as herein shown in the drawings, I provide a plate 1 on which the stamping 70 apparatus, designated generally at 3, and the clock 2 are separately supported. This is entirely optional, as the stamping apparatus may be rested or stood upon a table, desk, or other support and the clock stood 75 adjacent thereto. A pair of clock supporting elements 4 and 5 holding the clock 2 in vertical position adjacent the stamping apparatus 3. These supports 4 and 5 may be of any suitable or desired height to hold 80 the clock 2 with the central arbor 6 to which is secured a socket member 7, in appropriate position, to be joined with a co-operating socket 8 on the shaft 9 which extends from the stamping apparatus at right angles, as 85 will be explained.

With the clock thus positioned, it appears substantially as a part of the entire device, being applied at the front of the apparatus and therefore can be used as an efficient and 90 compact ornament. In fact, the arrangement of my present time stamping apparatus gives the appearance of the more expensive type of devices wherein the clock is built into the time stamping device, but 95 entirely without the disadvantages of such constructions.

The difficulty of having such an arrangement of clock and stamping devices is overcome by my present invention enabling the 100 clock to be wound or re-wound when thus positioned. It was impractical to remove the clock each time from the apparatus and yet as all these types of economical clocks— 105 which it was desired to use—are constructed to be re-wound from the back and as it was not feasible to provide such a clock with a winding mechanism at the top of the clock—the present arrangement was formerly considered impractical. However, I have pro- 110

vided winding means consisting in the key 10 fitted directly through the stamping apparatus 3, rotatable through the bored recesses in the sides of the stamping apparatus and adapted to fit directly onto the winding mechanism at 11 in the clock 2. A handle 12 of usual type is supplied to the head 14 of the key 10. As this handle is at the rear or back of the stamping apparatus on the same side with the ribbon winding reel 15, it is entirely out of the way and unobjectionable. This arrangement for the key 10 furthermore is of advantage in holding the clock 2 in proper alinement and position relatively with the stamping apparatus 3, particularly when the clock and stamping apparatus are separately resting upon a table, desk, or the like, instead of both being secured to the common supporting plate 1. The short shaft and direct means of uniting the clock and stamping apparatus is also desirable, more economical, requiring less power to operate and therefore insuring greater accuracy in the running of the clock than in former constructions. The clock being still separated from the time stamp is free of the injury and damage through the jars incident to the hammering of the time stamp through depression of the lever 40 and head 13.

My present invention is further described and claimed in the form of a claim as follows:

An automatic time stamping apparatus of the kind described, comprising a support, 35 a time stamping apparatus carried by the support, and constituting, with the support, a unitary structure, in combination with a commercial unitary time keeping element also mounted on the support at one side of 40 and in close proximity to, the time stamping apparatus, means on the time stamping apparatus to hold, aline, and transmit power from one relatively to the other and comprising a power transmitting shaft extending from the time keeping element to the stamping apparatus, and a winding key extending through the stamping apparatus, whereby the ordinary time keeping clock may be placed on one side of the stamping 50 apparatus and wound from the other side of such stamping apparatus.

In testimony whereof, I have signed my name to this specification, in the presence of two subscribing witnesses.

SIMON AGRANAT.
